L. TADDEO,
FOUNTAIN PEN.
APPLICATION FILED MAY 16, 1921.

Patented Mar. 14, 1922.

Inventor
Luigi Taddeo
by Mrs. M. Monroe
Attorney

UNITED STATES PATENT OFFICE.

LUIGI TADDEO, OF CLEVELAND, OHIO.

FOUNTAIN PEN.

1,409,617.

Specification of Letters Patent. Patented Mar. 14, 1922.

Application filed May 16, 1921. Serial No. 469,819.

To all whom it may concern:

Be it known that I, LUIGI TADDEO, a citizen of the United States, and resident of Cleveland, in the county of Cuyahoga and State of Ohio, have invented certain new and useful Improvements in Fountain Pens, of which I hereby declare the following to be a full, clear, and exact description, such as will enable others skilled in the art 10 to which it appertains to make and use the same.

This invention relates to an improved fountain pen of the type hereinafter described.

15 The main object of the invention is to provide a novel, simple, durable and efficient fountain pen, which includes concealed means for filling the chamber with ink, said filling means being so arranged as to 20 occupy a comparatively small amount of space within the chamber.

A further object of this invention is to provide a reciprocable plunger within the ink holding chamber of the pen, and a 25 plunger rod employed to operate the plunger which can be disconnected therefrom, and concealed within the chamber when the plunger is withdrawn to the outer end of said chamber after filling the pen.

30 Another object of the invention is to so construct my novel fountain pen as to furnish means for guiding the plunger, and plunger rod for making the opening in which the piston passes, fluid tight, and 35 means for providing an adjustable packing for the plunger adapted to prevent the passage of the writing fluid past it within the chamber.

The foregoing and such other objects as 40 may appear from the ensuing description are attained by the construction, arrangement, location and combination of the parts hereinafter more fully described, illustrated by the accompanying drawings, and partic- 45 ularly pointed out in the claims appended hereto.

In the accompanying drawings forming a part of this specification, it will be seen that:

50 Figure 1 is a longitudinal section of the device embodying my invention, showing the plunger in position to draw in the ink.

Fig. 2 is a similar view showing the plunger drawn back and the plunger rod 55 detached therefrom and pushed back within the chamber.

Fig. 3 is a perspective view of the several parts of the plunger in disconnected position, and

Fig. 4 is a side elevation of the plunger 60 rod.

Similar characters of reference are employed to designate like parts throughout the several views of the drawings.

In carrying out my invention as illustrated, A indicates the cylindrical chamber in which the ink is contained; B is a reciprocable plunger therein, and C is the reciprocable plunger rod which is adapted to pass through said plunger. 65

A guide opening D, for the plunger rod is formed in a bearing member E, in the outer end F, of the chamber and is preferably formed fluid tight. 70

F' is a cap adapted to cover the end of 75 the plunger rod when the pen is not in use; B, is the body of the plunger provided with an extended screw-threaded opening G, into which the enlarged screw-threaded inner terminal H, of the plunger rod is connected 80 when the said rod is employed to operate the plunger.

When the plunger has been caused to assume the position shown in Fig. 2, the plunger rod can be disconnected from the extended opening G and pushed back within the chamber ready for use again when the contents of the chamber have been discharged. A compressible packing washer I, is employed to prevent leakage of ink past 90 the plunger and is adjustably compressed between the body B, of the plunger and the hard rubber body disk J, by means of the screw-threaded extension K forming a part of said disk, which is adjustably screwed 95 into the opening G. Said washer I is preferably made of felt or other suitable compressible material which will form a liquid-tight joint with the inner wall of the chamber. 100

The plunger rod is passed through an opening K' formed through the disk J, and is packed so as to prevent ink from passing around it by means of an outer hard rubber clamping disk L, and the intermediate resilient washer M formed of soft rubber. 105

It will be perceived that the outer face of the body disk J is recessed for the reception of the soft rubber disk M, and the disk L, formed of hard rubber, and formed within the outer face of said disk J is a central recess N, while the inner face of the clamp- 110

- ing disk L is formed with a similar recess L', whereby when the plunger rod is disconnected from the plunger body B, and moved back and forth through said plunger, 5 the washer M, will be caused to vibrate and enter one or the other of the central recesses formed in the disks J and L, respectively, and at the same time tightly embracing said rod and forming a fluid tight connection between 10 said soft rubber washer and the plunger rod.
- The outer terminal of the rod is provided with a knob O, or other holding means, suitable for grasping with the fingers, while the 15 inner enlarged screw-threaded terminal of said rod renders it impossible to withdraw the rod through the plunger or through the wall of the chamber until the bearing member therein has been removed.
- 20 It will be readily evident that when the washer I becomes worn or loose and fails to make the desired tight contact with the inner wall of the chamber A, so as to properly draw the ink into said chamber, it can be 25 easily spread at its peripheral edges to increase its diameter by compressing it between the adjustable disk J, and the plunger body B, thereby materially increasing its efficiency and longevity.
- 30 By reference to Fig. 2, it will be seen that the plunger rod C can be easily detached from the plunger and positioned within the chamber A, after filling the pen with ink, and that it is quite easy and convenient to 35 turn said rod so as to thread its inner threaded terminal within the screw-threaded extension G of the plunger, when it is desired to operate the plunger for filling the pen.
- 40 Having thus described my invention what I claim and desire to secure by Letters Patent is:

1. A fountain pen comprising the hollow body, a reciprocable plunger therein formed with a central dependent screw-threaded 45 opening in the lower face of its body, a body disk having a dependent screw-threaded extension adjustably fitted in said opening and formed with a concave recessed upper face, an outer hard clamping disk and a soft 50 rubber washer seated within said recessed face, a compressible washer fitted between said body and body disk, a plunger rod having an enlarged screw-threaded inner terminal adapted to detachably engage with 55 said dependent opening, said rod passing through said disks and washers, and the opposed face of the body disk and the hard clamping disk each being provided with a central recess for the purposes set forth. 60
2. A fountain pen comprising the hollow body, a plunger therein composed of a body member of hard material having a downwardly extended screw-threaded opening, a hard rubber body disk provided with a central screw-threaded downwardly extended portion fitted within said opening and a recessed upper face, a clamping disk of hard material and a resilient washer fitted within said recessed face, a compressible washer 70 fixedly fitted between said body member and body disk, said washer extending transversely across the plunger and adapted to be spread outwardly by the relative tightening of the body member and body disk, and a 75 plunger rod detachably secured to said plunger.

In testimony whereof, I hereunto set my hand this 2nd day of May, 1921.

LUIGI TADDEO.

In presence of—

W.M. M. MONROE,
SOL W. WYMAN.
